(57) **CLAIM**

The ornamental design for a two-piece bucket holder as shown and described.

DESCRIPTION

FIG. 1 is a top-front perspective view of a two-piece bucket holder, comprised of a bucket hook and a key;

FIG. 2 is a rear-bottom perspective view of the two-piece bucket holder;

FIG. 3 is a front side elevational view of the two-piece bucket holder;

FIG. 4 is a rear side elevational view of the two-piece bucket holder;

FIG. 5 is a left side elevational view of the two-piece bucket holder;

FIG. 6 is a right side elevational view of the two-piece bucket holder;

FIG. 7 is a top plan view of the two-piece bucket holder;

FIG. 8 is a bottom plan view of the two-piece bucket holder;

FIG. 9 is a rear-side perspective view of the key of the two-piece bucket holder;

FIG. 10 is a first bottom-side perspective view of the key of the two-piece bucket holder;

FIG. 11 is a second bottom-side perspective view of the key of the two-piece bucket holder;

FIG. 12 is a front side elevational view of the key of the two-piece bucket holder;

FIG. 13 is a rear side elevational view of the key of the two-piece bucket holder;

FIG. 14 is a left side elevational view of the key of the two-piece bucket holder;

FIG. 15 is a right side elevational view of the key of the two-piece bucket holder;

FIG. 16 is a top plan view of the key of the two-piece bucket holder;

FIG. 17 is a bottom plan view of the key of the two-piece bucket holder;

FIG. 18 is a top-front perspective view of the bucket hook of the two-piece bucket holder;

FIG. 19 is a front side elevational view of the bucket hook of the two-piece bucket holder;

FIG. 20 is a rear side elevational view of the bucket hook of the two-piece bucket holder;

FIG. 21 is a left side elevational view of the bucket hook of the two-piece bucket holder;

FIG. 22 is a right side elevational view of the bucket hook of the two-piece bucket holder;

(Continued)

FIG. 23 is a top plan view of the bucket hook of the two-piece bucket holder; and,
 FIG. 24 is a bottom plan view of the bucket hook of the two-piece bucket holder.
